CLOTHESRACK

Timothy Ford, Lexington, Ky.

Application January 26, 1933. Serial No. 653,719

1 Claim. (Cl. 211—178)

This invention appertains to new and useful improvements in supports and more particularly to a novel clothes rack.

The principal object of the present invention 5 is to provide a clothes rack for either indoor or outdoor use which is constructed in such a manner as to permit collapsibility for storage in a small space.

Another important object of the invention is to 10 provide a clothes rack which can be easily extended to position for use and which is constructed in such a manner as not to be susceptible to the development of ready defects.

These and various other important objects and 15 advantages of the invention will become apparent to the reader of the following specification.

In the drawings:

Figure 1 represents a top plan view of the rack.

Figure 2 represents a side elevational view of 20 the rack.

Figure 3 represents a horizontal sectional view taken substantially on line 3—3 of Figure 2.

Figure 4 represents a fragmentary elevational view with parts broken away so as to disclose the 25 brace retaining means.

Figure 5 represents a fragmentary vertical sectional view taken substantially on line 5—5 of Figure 1.

Figure 6 represents a sectional view taken on 30 substantially the same line 5—5, showing the parts collapsed.

Figure 7 represents a fragmentary vertical sectional view through the post, showing the same equipped with a stake for outdoor use.

35 Figure 8 represents a horizontal sectional view taken substantially on line 8—8 of Figure 7.

Referring to the drawings wherein like numerals designate like parts, it can be seen in Figure 2, that numeral 5 represents a vertical post 40 of polygonal cross section; the same being provided with brace legs 6 at its lower end portion.

At circumferentially spaced intervals, arm members 7 are hingedly connected to the upper portion of the post by hinge members 8 and are 45 capable of swinging upwardly in the manner shown in Figure 6.

Each of these arms is hingedly connected as at 9 to the upper end portion of a prop 10, at one side thereof, while hingedly connected at 11 50 to the opposite side of this prop at the same end portion is a supplemental arm 12. Each of these arms 12 is equipped with a brace member 13 hingedly secured to the intermediate portion of its bottom side as at 14.

55 Reference to Figure 4 will show that the lower

end of each of the brace members 13 is equipped with an angle member 15, the depending portion of which is provided with an opening through which pins 16 can be inserted to bite into the 60 aforementioned prop for supporting the corresponding supplemental arm 12 in the horizontal position clearly shown in Figure 5.

As is clearly shown in Figure 1, the outer end of each of the supplemental arms 12 is provided with a pair of eyelets 17 disposed horizontally in 65 opposite directions. One eyelet 17 of each arm 12 has a cable or line of some strand material extending therefrom and this line is provided with a hook 18 at its free end which is engageable with the remaining type of eyelet on the next 70 adjacent supplemental arm 12.

The upper ends of the prop 10 are likewise provided with eyelets 20 in opposite directions and hook and line members 21 are employed for connecting these eyelets on adjacent props. 75

Extending from the post 5 and underlying each of the arms 7 at a point spaced below the said arm 7 is an arm 7' hingedly supported in the same manner and to the intermediate portion of the corresponding prop 10. Underlying each of the supplemental arms 12 is another supplemental arm 12' mounted in the same manner as the overlying arm 12 and hingedly connected to the intermediate portion of the corresponding prop 10. 80

By referring to Figures 5 and 6, it will be seen that the intermediate portion of each of the props 10 is provided with an eyelet 22 and when the prop and arm are swung to the collapsed position shown in Figure 6, a hook 23 is employed for 90 retaining the parts in this collapsed position.

Obviously, when the legs 6 are employed as shown in Figure 2, the rack is adaptable for indoor use.

For outdoor use, a stake 24 is driven into the 95 ground as shown in Figure 7 and hook members 25 extending through the post 5 have their hooked ends engaged with the stake so as to retain the post line in upright position. These hook members 25 can be threaded to engage with the notch 100 26 so that the same can not become displaced from clamped engagement with the stake 24.

While the foregoing specification sets forth the 105 invention in specific terms, it is to be understood that numerous changes in the shape, size and materials may be resorted to without departing from the spirit or scope of the invention as claimed hereinafter.

Having described the invention, what I claim as 110 new is:

A support of the character described comprising a post, an arm extending laterally from the said post and being hingedly connected thereto, an upstanding member supported at its lower end upon the ground, a hinged connection between the outer end of the said arm and the said up-

right, a supplemental arm hingedly connected to the said upright adjacent the first mentioned arm, and brace means for the said supplemental arm interposed between the said supplemental arm and the said upright.
